UNITED STATES PATENT OFFICE.

JACOB C. CHAMBERLAIN, OF NEW YORK, N. Y.

DEVICE FOR UNLOADING, RECHARGING, AND RELOADING ELECTRIC-CAR STORAGE-BATTERIES.

SPECIFICATION forming part of Letters Patent No. 433,851, dated August 5, 1890.

Application filed April 24, 1890. Serial No. 349,398. (No model.)

To all whom it may concern:

Be it known that I, JACOB CHESTER CHAMBERLAIN, a citizen of the United States, residing in the city, county, and State of New York, have invented certain new and useful Improvements in Devices for Unloading, Recharging, and Reloading Electric-Car Storage-Batteries, of which the following is a specification.

10 This invention relates to those systems of electric traction in which the current is derived from storage-batteries or accumulators located upon the car itself, the purpose of the invention being to enable the substitution of 15 charged for exhausted batteries in the most expeditious, economical, and effective manner possible.

This application comprises certain improvements on the invention described in my application, Serial No. 317,008.

Referring to the accompanying drawings, which form a part of this specification, Figures I and II are respectively end and side elevations, partly in section, of my improved 25 battery-rack and related features of improvement.

Each "slip" or "charging-stall" combines the following instrumentalities:

1 represents a pair of rails of an ordinary 30 street-car track or a branch thereof.

2 represents part of the running-gear of a street-car, and 2' 2", respectively, represent parts of the bed or body and of a bed-sill. The 35 spaces under the seats are utilized in the customary way as receptacles or closets 3 to receive and hold batteries 4, which when housed within said closets are coupled up with each other and with the motor in any approved way.

The rack shown in the present application 40 has several features in addition to those described in my former application, which features relate to extending the capacity of the rack and facilitating the shifting of the batteries.

45 Interposed between the carrier or elevator and the car is an additional rack or tier of charging-benches, making in all four racks 42 43 44 45. This practically doubles the capacity of the rack without largely increasing the size and expense of the construction.

The batteries from the car are run across the bridge 47 and through the compartments of the inner rack, which is on a level therewith, onto the elevator or carrier 12 12', which carries them to the shelf whereto they are to be 55 transferred. The inner racks 43 44 are provided with rests 46 for the draw-bridges 47.

To enable the operator to have easy access to the high shelves of the racks, I provide what I term the "workman's platform" 48, 60 which is connected by cables 49 to the hoist or carrier in such a manner that it follows to some extent the movement of the latter, so that the workman on the platform will always be in convenient working proximity to the 65 carrier and can easily reach the batteries on the carrier and the shelves opposite the same. A lost motion by a slot 50 and stop 51 is provided between the cable and workman's platform, so that the workman's platform does 70 not begin to move until the carrier has moved up out of convenient reach of the workman.

The winches 18 for operating the hoist-cable are driven by motors 52, of any suitable form, preferably electric motors, and controlled by 75 friction-clutches 53, whose operating devices—such as handles 54—are connected by intermediate mechanism—such as connecting-rods 55 and levers 56—to a common operating point or station 57. Counter-weights 80 58 are provided for the carriers, being connected thereto by cables in an obvious manner.

Having thus described my invention, the following is what I claim as new therein and 85 desire to secure by Letters Patent:

1. In a device for unloading, recharging, and reloading electric-car batteries, the combination, with the double rack adapted to receive and charge the batteries, of the interposed carrier, substantially as shown and described.

2. In a device for unloading, recharging, and reloading electric-car batteries, the combination, with the battery-racks, of the battery-hoist and the workman's platform connected to and operated by the battery-hoist, substantially as shown and described.

3. The combination, with the battery-racks, of the battery-hoist, the workman's platform 100

connected thereto, and the connection having loose motion when the platform is down, substantially as and for the purposes set forth.

4. In a device for unloading, recharging, and reloading electric-car batteries, the combination, with the battery-racks, of the two hoists and the operating devices for the two

hoists controlled from a single point, substantially as shown and described.

J. C. CHAMBERLAIN.
